COUPLER MOUNTING

William J. Metzger, Euclid, Ohio, assignor to National Malleable and Steel Castings Company, Cleveland, Ohio, a corporation of Ohio

Application June 26, 1941, Serial No. 399,800

17 Claims. (Cl. 213—4)

This invention relates to a coupler and draft rigging arrangement for use particularly in the pilot of a locomotive.

An object of the invention is to provide a new and improved coupler and draft rigging arrangement for use in a locomotive pilot, the arrangement being mounted so as to pivot about a horizontal axis to permit swinging of the coupler from normal horizontal operative position to inoperative position within the pilot contour.

Another object of my invention is to provide a drop coupler arrangement for use in the pilot of a locomotive which arrangement is of simple and sturdy construction and which permits movement of the coupler from operative to inoperative position with a minimum amount of effort and time.

A more specific object is to provide a coupler, yoke and draft gear assembly which is contained in a member pivotally mounted in the pilot of a locomotive, the coupler being adapted to be swung downwardly to a position within the pilot contour when not in service.

A further object is to provide a coupler, yoke and draft gear unit for a locomotive pilot in which no dead weight is required to counterbalance the coupler, the unit being mounted within the pilot for pivotal movement about a horizontal axis to permit swinging of the coupler from normal operative position to inoperative position within the pilot.

A still further object is to provide a coupler, yoke and draft gear assembly for a locomotive pilot whereby the coupler and yoke are resiliently supported to permit vertical angling of the coupler and yoke, the entire assembly being carried by a member pivotally mounted within the pilot about a horizontal axis.

An additional object is to provide a drop coupler and associated uncoupling mechanism for use in a locomotive pilot whereby upon movement of the coupler into and out of operative position the uncoupling mechanism is automatically engaged and disengaged.

Other objects and advantages of the invention will be apparent from the following description taken in conjunction with the drawings, in which:

Figure 1 is a central vertical sectional view through the pilot of a locomotive showing an embodiment of the invention.

Figure 2 is a view partly in horizontal section and partly in plan of the mechanism shown in Figure 1.

Figure 3 is a transverse vertical sectional view, taken along line 3—3 of Figure 2.

Figure 4 is a view similar to Figure 1 but showing the coupler lowered to a position within the pilot.

Figure 5 is an enlarged partial view, taken along line 5—5 of Figure 2; and

Figure 6 is a side view of the supporting member of the mechanism.

Referring to the drawings, there is shown the forward portion 10 of the locomotive frame having a pilot beam 11. To the frame is secured the pilot 12. The frame is formed with spaced end portions 13 between which is adapted to be received the housing or supporting member 14 which carries the coupler, draft gear and yoke. Member 14 is pivotally mounted for movement in a vertical direction by means of horizontally disposed pins 15. Each pin is supported in the locomotive frame by a vertically adjustable bearing member 16 which is provided with mounting lugs 17 in engagement with wall 18 of the frame. Wall 18 has an elongated opening 19 which receives boss 20 of member 16, leaving a clearance above the boss. Adjacent boss 20 member 16 has an inwardly projecting portion 21 positioned opposite boss 22 of member 14. The pin receiving openings in bearing member 16 and in boss 22 are lined with wear-resistant bushings 23 and 24, respectively. A segmental flange 25 extends from portion 21 into overlapping engagement with boss 22 of member 14, thereby supplementing pins 15 in resisting buffing stresses transmitted thereto. Members 16 are secured to walls 18 by means of bolts 26 and shim washers 27. Bolt receiving openings 28 are elongated in a vertical direction so that with member 16 positioned as shown in the drawings, projection 29 of each washer occupies the space above the bolt. Whenever it is desired to increase the height of the coupler above the track, washers 27 may be reversed so that projections 29 underlie bolts 26, thereby raising the coupler by that amount. It will be understood that various sizes of washers may be used depending upon the height to which the coupler is to be raised. Stops 30 and 31 are provided on walls 18 adjacent lugs 17 so that buffing and draft loads will be transmitted through member 16 to the walls, thus relieving bolts 26 of those forces. Pins 15 are retained in place by means of bolts 32 which bridge lugs 33 on member 16. Housing member 14 is adapted to carry and support the draft gear 35, the yoke 36 and the coupler 37. The draft gear is directly supported by the tie plate 39 which extends across the bot-

tom of member 14 and is secured thereto by bolts 40. Plate 39 in addition to supporting the draft gear increases the rigidity of member 14 and being substantially entirely on the side of pins 15 opposite to that of the coupler serves to counterweight the latter. Member 14 is provided with buffer stops 41 and draft stops 42 for engagement with the draft gear.

Yoke 38 embraces the draft gear and functions with respect thereto in the usual manner. The yoke is resiliently supported within member 14 by means of the resilient supporting arrangement 45 at the forward end thereof. Relative pivotal movement between the draft gear and yoke in a vertical direction is provided by forming the engaging surfaces between the ends of the gear and yoke curved vertically about a point substantially midway between the ends of the gear. Thus the coupler may angle vertically without distorting the draft gear or disturbing the engagement between the draft gear and stops 41 and 42.

Supporting arrangement 45 comprises arms 46 depending from member 14 to which is bolted the tie member 47 having a horizontal portion 48 and transversely extending vertical walls 49. A spring 50 rests on portion 48 and is positioned thereon by means of boss 51. Positioned between walls 49 and supported on spring 50 is the carrier member 52. Arms 46 are recessed as at 53 so as to receive extensions 54 on member 52 and thereby limit vertical movement thereof. During normal horizontal position of the coupler, extensions 54 are in engagement with the upper walls of recesses 53. Downward movement of member 52 is limited by the lower surface 55 of each recess so that spring 50 cannot be subjected to any oversolid blows. However, sufficient downward movement is provided to permit the amount of vertical angling of the coupler that is necessary in service. Interposed between the bottom of the yoke and member 52 is a wear plate 56 which may be welded to the yoke.

It will be noted that the top horizontal connecting wall 60 of member 14 and the lower tie plate 39 are so formed and spaced apart as to leave sufficient clearance above and below the upper and lower straps, 61 and 62 respectively, of the yoke to allow for vertical movement thereof during vertical angling of the coupler.

The coupler is connected to the yoke by means of a vertical pin 65, thereby permitting horizontal angling of the coupler. The yoke is provided with a forwardly extending shelf 66 which serves to support the coupler. An opening 67 is provided through the resilient supporting arrangement 45 to facilitate removal of pin 65. Any suitable member may be inserted therethrough to raise the pin upon removal of pin-retaining bolt 68.

Pins 15 which pivotally mount the housing member are so located with respect to the member, the yoke, and the coupler that there is a slight preponderance of weight on the coupler side of the pivotal axis of the unit. In other words, with the assembly free to pivot about pins 15 it will assume a tilted position with the coupler side lowered. From such position the coupler may be swung very easily either to normal horizontal position or to completely lowered position within the pilot as shown in Figure 4. A workman will thus be able very quickly and without undue exertion to lower the coupler from normal operative position to a position within the pilot or vice versa. It will be understood that

although the pivotal axis of the unit has been located so that there is a slight excess of weight on the coupler side thereof, it may be located in accordance with any summation of moments thereabout that may be desired. For example, the axis may be located so that in horizontal position of the coupler the unit is balanced and will therefore tend to remain in such position, or the axis may be made to pass through the center of gravity of the unit so that the coupler will theoretically remain in any position it is placed.

The assembly is locked in either operative or lowered position of the coupler by means of locking pins 70. These pins are slidably mounted in members 16 and are adapted to be projected into openings in bosses 71 and 72 on member 14. To facilitate manipulation of the locking pins each may be provided with an operating handle 73 pivoted to member 16 by means of a bolt 74. The outer end of each pin is slotted as at 75 to receive the handle, and the connection between the pin and handle is accomplished by means of an elongated slot 76 in the handle and a bolt 77 passing through the pin and through slot 76. It will be clear that upon raising handle 73 pin 70 may be withdrawn from the housing member, thereby permitting pivoting of the entire assembly about pins 15. An arcuate rib 78 connects bosses 71 and 72. The end surface of this rib lies in the plane of the end surface of the bosses and is so located that pin 70 can be projected only into bosses 71 or 72, depending upon whether the assembly is to be locked in operative or inoperative position of the coupler. Handle 73 may be locked in projected position of pin 70 by means of a hook 79 adapted to engage a lug 80 on the handle, thereby precluding raising of the handle. The hook may be fastened to the pilot by means of a chain 81. It will be understood, however, that any suitable means for locking the handle may be utilized. A stop 82 integral with the pilot is provided to limit downward swinging of the coupler by engagement with the pin protector lug 83 on the coupler. During raising of the coupler to operative position the end portion of bottom wall 84 of the locomotive frame is adapted to engage tie plate 39 to limit downward movement of the rear end of the unit, thereby facilitating positioning of the coupler to permit projection of locking pins 70 into bosses 72. Although two locking pins have been shown it is to be understood that the device may be provided with only one of such pins, as no undue stresses are normally applied thereto.

The apparatus for uncoupling the coupler requires no disconnection of any of its parts before the coupler can be lowered to inoperative position within the pilot, and upon raising of the coupler to operative position the mechanism is automatically returned into position to operate the coupler. Furthermore, the apparatus is of symmetrical construction so that it is operable from either side of the coupler. The coupler is provided with a rotor lever 96 and link 91. A bail member 92 is pivotally connected to housing member 14 by means of a pair of brackets 93 secured to front wall 49 of tie member 47. The bail is formed with a horizontal central portion 94 which is operatively connected to link 91. Each end of the bail has a lever portion 95 which extends rearwardly from bracket 93 and is concentrically curved about the axis of pivot pins 15. A rotor link 96 for actuating the bail is

pivotedly mounted in the pilot on each side of the bail by means of brackets 97 and 98. Each link 96 is provided with a horizontal arm 99 which overhangs the arcuate lever portion 95 of the bail and is adapted to engage therewith upon pivotal movement of the link to operate the bail and effect uncoupling of the coupler. Since the lever portion 95 is arcuately curved it will pivot clear of arm 99 upon lowering of the coupler from operative to inoperative position. A handle member 100 is pivotally mounted in brackets 101 and is joined to rotor link 96 by an intermediate connecting link 102. It will be clear that the lifting force transmitted to rotor link 96 upon raising of handle 100 will cause arm 99 to be swung into engagement with lever portion 95 of the bail and cause the latter to pivot in brackets 93, thereby transmitting the lifting force to rotor lever 90 through link 91 to uncouple the coupler. Furthermore, there is sufficient clearance between arm 99 and lever portion 95 when the mechanism is at rest so that when the height of the coupler above the track is increased in the manner previously explained, the arm will still be clear of the lever portion and the apparatus will remain in operative condition. It will be noted that the preponderance of the weight of the bail is forward of its pivot point and therefore exerts a downward force on link 91 and rotor lever 90, thereby opposing any creeping upward of the coupler lock.

The pilot 12 may be of any suitable shape and is firmly secured to the locomotive frame by vertically spaced bolts 105 and horizontally spaced bolts 106 and 107. The front of the pilot is recessed to permit swinging of the coupler to inoperative position within the pilot and to permit access to handles 73 for manipulation of locking pins 70. The rear portion of the pilot is recessed as at 108 thereby permitting removal of the pilot from the frame without the necessity of removing the coupler or housing member 14. The uncoupling mechanism, however, must be disconnected before removal of the pilot, but this may be easily accomplished by disconnecting brackets 97 and sliding each of links 96 laterally outwardly an amount sufficient to clear arm 99 from lever 95 of the bail. Upon disconnection of brackets 101 from the locomotive frame and removal of securing bolts 105, 106 and 107 the pilot may be withdrawn.

In order to provide a smooth front to the locomotive when the coupler has been lowered to inoperative position the pilot opening may be closed by any suitable cover arrangement.

It will be apparent that the invention provides a compact coupler and draft rigging unit for use particularly in the pilot of a locomotive in which it is required that the coupler be capable of being withdrawn from its normal operative position when not in service. The unit is simple in construction and the coupler may be moved very easily and quickly to inoperative position within the pilot. In addition to the provision of a draft gear for cushioning draft and buffing forces, the arrangement provides for both vertical and horizontal angling of the coupler. The coupler, yoke and draft gear are all carried by a member which is supported by the locomotive frame independently of the pilot member which is therefore relieved of all buffing and draft forces transmitted by the coupler.

The terms and expressions which I have employed are used as terms of description and not of limitation, and I have no intention, in the use

of such terms and expressions, of excluding any equivalents of the features shown and described or portions thereof, but recognize that various modifications are possible within the scope of the invention claimed.

What I claim is:

1. In a locomotive pilot a coupler and draft rigging assembly comprising a support member pivotally mounted for movement about a horizontal axis and adapted to support a draft gear, coupler and yoke, a draft gear and a yoke encircling said draft gear supported by said member in operative relation, and a coupler connected to said yoke and in normal operative position extending from the pilot, said member being adapted to be pivoted about said axis so as to swing said coupler to inoperative position within the pilot.
2. In a locomotive pilot a member pivotally mounted for movement about a horizontal axis and adapted to support a draft gear, coupler and yoke, stop lugs on said member, a draft gear carried by said member and adapted to engage said lugs, a yoke carried by said member embracing said gear, and a coupler connected to said yoke and extending from the pilot when in normal operative position, said member being adapted to be pivoted about said axis so as to swing said coupler to inoperative position within the pilot.
3. In a locomotive pilot a coupler and draft rigging assembly comprising a member pivotally mounted for movement about a horizontal axis and adapted to support a draft gear, coupler and yoke, a draft gear and a yoke encircling said draft gear carried by said member in operative relation, and a coupler connected to said yoke and in normal operative position extending from the pilot, said horizontal axis being positioned so as to pass approximately through the center of gravity of said assembly.
4. In a locomotive pilot a counterbalanced coupler unit comprising a housing member adapted to carry a draft gear and a yoke in operative relation, said draft gear being encircled by said yoke, a coupler supported by and connected to said yoke, said coupler in normal operative position extending from the pilot, and means for pivotally mounting said member to enable pivotal movement of said unit about a horizontal axis so as to swing said coupler to inoperative position within the pilot.
5. A coupler and draft rigging unit for use in the pilot of a locomotive, said unit comprising a housing member adapted to carry in operative relation a draft gear and a yoke, said yoke encircling said draft gear, a coupler connected to and supported by said yoke, and means on said member for pivotally mounting said unit about a horizontal axis which passes approximately through the center of gravity thereof.
6. A coupler and draft rigging unit for use in the pilot of a locomotive, said unit comprising a housing member adapted to carry in operative relation a draft gear and a yoke, said yoke surrounding said draft gear and being resiliently supported to enable vertical angling thereof, a coupler pivotally connected to said yoke for horizontal angling with respect thereto, and means for pivotally mounting said member about a horizontal axis, said means being so positioned that said coupler is counterbalanced by said member, draft gear, and yoke.
7. In a locomotive pilot, a coupler and draft rigging unit pivotally mounted in the pilot for movement about a horizontal axis, said unit com-

prising a housing member pivotally mounted on a horizontal axis in said pilot and adapted to support a draft gear, a yoke and a coupler, a draft gear in said housing member, a yoke encircling said draft gear adapted to angle vertically relative thereto, a coupler pivotally connected to said yoke for horizontal angling, and means in said housing member for resiliently supporting said yoke to enable vertical angling of said yoke and coupler relative to said draft gear.

8. In a locomotive pilot a counterbalanced coupler unit comprising a member pivotally mounted in the pilot for movement about a horizontal axis, a draft gear supported by said member, a yoke embracing said draft gear and supported by said member, a coupler connected to said yoke and in normal operative position extending from the pilot, said coupler being supported by said member, said unit being adapted to be pivoted about said axis so as to move said coupler to inoperative position within the pilot, and means for locking said unit in said operative or in said inoperative position of said coupler.

9. In a locomotive pilot a counterbalanced coupler unit comprising a member pivotally mounted in the pilot for movement about a horizontal axis, a draft gear supported by said member, a yoke embracing said draft gear and supported by said member, a coupler connected to said yoke and in normal operative position extending from the pilot, said coupler being supported by said member, said unit being adapted to be pivoted about said axis so as to move said coupler to inoperative position within the pilot, and means for locking said unit in said operative or in said inoperative position of said coupler, said means comprising a pin adapted to be projected into an opening in said member.

10. In a locomotive pilot a frame structure having a pair of spaced vertical walls, a member positioned between said walls and pivotally connected thereto for movement in a vertical direction, said member being constructed and arranged to carry a coupler, yoke and draft gear assembly, and resilient support means carried by said member and supporting said assembly to enable vertical angling of the coupler.

11. In a locomotive pilot a member for carrying a coupler, yoke and draft gear unit in raised operative position and in lowered inoperative position, said member being pivotally mounted for movement about a horizontal axis, and resilient support means carried by said member for supporting said unit, said means comprising arms depending from said member, a tie member connecting said arms, a spring on said tie member, and a support member interposed between the top of said spring and said unit.

12. In a locomotive pilot a frame structure having a pair of spaced vertical walls, a member positioned between said walls adapted to carry a coupler, yoke and draft gear assembly, and means for pivotally connecting said member to said walls to permit movement of said coupler from normal operative position to inoperative position within the pilot, said means comprising vertically adjustable members secured to said walls, and horizontal pins received in said last named members and extending into said first named member.

13. In a locomotive pilot a frame structure having a pair of spaced vertical walls, a member positioned between said walls adapted to carry

a coupler, yoke and draft gear assembly, means for pivotally connecting said member to said walls to permit movement of said coupler from normal operative position to inoperative position within said pilot, and means for locking said member in either said operative or said inoperative position of said coupler, said means comprising a pin adapted to be projected from one of said walls into an opening in said member.

10 14. In a locomotive pilot a frame structure having a pair of spaced vertical walls, said walls having aligned openings therein, vertically adjustable bearing members secured to said walls and having portions extending into said openings, said openings being elongated so as to enable adjustment of said members in a vertical direction, a member received between said walls and adapted to carry a coupler, yoke and draft gear assembly, and pin means mounted in said bearing members and extending into said last named member to pivotally mount the latter so as to enable movement of said assembly from operative position of the coupler to lowered position thereof within the pilot.

25 15. In a counterbalanced coupler, yoke and draft gear assembly for use in the pilot of a locomotive, a supporting member providing a support for a yoke, coupler and draft gear, said member comprising spaced portions providing a pocket for the draft gear and yoke, said yoke encircling said draft gear, means for pivotally mounting said member in the pilot to permit swinging of the coupler from operative position to inoperative position within the pilot, and means enabling locking of said member in either operative or inoperative position of the coupler.

16. In a locomotive pilot a member pivotally mounted for movement about a horizontal axis, a coupler carried by said member and in normal operative position extending from the pilot forwardly of said axis, said member being adapted to be pivoted about said axis so as to move said coupler from operative to inoperative position within the pilot, said member extending rearwardly of said axis so as to provide a counterbalance for said coupler, means comprising a pin adapted to be projected into an opening in said member to lock the latter in said operative or in said inoperative position of said coupler, and a pivotally mounted handle member connected to said pin and adapted to withdraw said pin from said opening upon being raised.

17. In a locomotive pilot a member pivotally mounted for movement about a horizontal axis, a coupler carried by said member and in normal operative position extending from the pilot forwardly of said axis, said member being adapted to be pivoted about said axis so as to move said coupler from operative to inoperative position within the pilot, said member extending rearwardly of said axis so as to provide a counterbalance for said coupler, and means for locking said member in said operative or in said inoperative position of said coupler, said means comprising a pin adapted to be projected into an opening in said member, said pin being slotted at one end, a pivotally mounted handle member extending into said slot, and means operatively connecting said pin and handle member, said handle upon being raised being adapted to withdraw said pin from said opening.

WILLIAM J. METZGER.
